CLAIM

I claim the ornamental design of a deer feeder, as shown and described.

DESCRIPTION

FIG. 1 is a perspective view of the deer feeder showing its intended use strapped to a tree in the native environment of deer.

FIG. 2 is a perspective view of the deer feeder.

FIG. 3 is a front view of the deer feeder.

FIG. 4 is a side view of the deer feeder.

FIG. 5 is a back view of the deer feeder.

FIG. 6 is a top view of the deer feeder; and,

FIG. 7 is a bottom view of the deer feeder.

The article is a deer feeder with a feed trough that has a cap for the top of the deer feeder and a hood for the feed trough. The broken lines showing the outline of straps and the native environment for deer in FIG. 1 are for illustrative purposes only and form no part of the claimed design.
